JOHN F. TINSLEY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

BOBBIN SUPPORT FOR WEFT REPLENISHING LOOMS

Application filed December 3, 1928. Serial No. 323,217.

This invention relates to improvements in bobbin supports for weft replenishing looms and it is the general object of the invention to provide a yieldable bobbin support with 5 a flexible or inherently resilient covering which will present to the bobbin a smooth surface along which the weft end of the bobbin may extend.

In the form of bobbin support shown in 10 co-pending application Ser. No. 251,992 filed by King there is set forth a bobbin support formed of a piece of wire coiled on itself in the form of a helix. The coils are wound of substantially the same diameter and in the 15 lower end of the spring there is inserted a bobbin supporting tip or plug made preferably of fiber or some similar material. The lowest coil forms with the tip a small crevice or crack into which the weft end of a bobbin 20 moving toward transfer position may fall. When this happens the weft end breaks at the time of transfer with resultant stoppage of the loom. It is an important object of my present invention to provide a cover for the 25 tip and a portion at least of the coil spring to give said support a continuous smooth surface along which the bobbin and its thread may slide.

In multicolor weft replenishing mechanisms there is usually employed a so-called cradle which rocks on its axis to discharge 30 a bobbin from one of the reserve stacks so that said bobbin may move toward transfer position. In being discharged the bobbin is 35 given a quick downward movement and it occasionally happens that this movement will cause a slight amount of rebounding which may leave the bobbin imperfectly placed with respect to the transfer hammer at the time of 40 transfer. By covering a portion or all of the support with a flexible surface which also has a relatively high coefficient of friction, such for instance, as rubber, I am able to retard the downward movement of the bobbin 45 sufficiently to prevent the rebounding but not enough to cause the bobbin to arrive too late under the transference hammer.

In previously made coil spring bobbin supports the coils have all been wound closely 50 together with the result that if the lower end

of the support be subjected to pressure acting along the axis of the support toward the holder for the latter said support will be unable to yield except by breakage, due to the fact that the coils are closed. If certain of the coils are spaced to permit compression there is danger that the weft end extending from the bobbin will become entangled with 55 said open coils in a manner similar to the entanglement caused when the previously mentioned supporting tip or plug is used. It is a further object of my invention to use an elastic covering for the open coils of the support so that said coils will not be exposed to the weft ends and a continuous smooth surface will be presented to the bobbin and its 60 weft, the support at the same time being compressible by a force acting substantially parallel to its axis.

With these and other objects in view which will appear as the description proceeds, my invention resides in the combination and arrangement of parts hereinafter described and set forth in the claims.

In the accompanying drawings wherein I 70 have shown two specific uses for my invention,

Fig. 1 is a vertical transverse section through a four-color magazine showing the same equipped with the preferred form of 80 support,

Fig. 2 is a horizontal section on line 2—2 of Fig. 1,

Fig. 3 is an enlarged detailed vertical section on line 3—3 of Fig. 1,

Fig. 4 is a view similar to a section on line 85 4—4 of Fig. 3 but with a modified form of bobbin support,

Fig. 5 shows the action of the form of support shown in Fig. 4 when engaged by a misplaced bobbin, and

Fig. 6 is an enlarged detailed longitudinal section on line 6—6 through the lower end of the forward bobbin support shown in 90 Fig. 1.

Referring to Figs. 1 and 2, I have provided a magazine designated generally at M having an outer plate 10 provided with vertical spaced bobbin tip receiving slots or guides 11. The opposite side of the magazine is 100

provided with an inner plate 12 having spaced vertical grooves or guides 13 for the butts of the bobbins. Each guide 11 with its corresponding guide 13 forms a guideway or compartment for a stack of bobbins.

5 In order to connect the inner and outer plates there is provided a plurality of tie rods 14 which hold the outer plate 10 spaced at the proper distance from the inner plate to accommodate the bobbins B. Located at 10 the bottom of each compartment is an oscillating bobbin control or cradle 15, and mechanism not shown rocks the cradles to deliver bobbins from the magazine stacks so they may move toward transfer position.

15 The lay L is of the usual form and may carry a shuttle S which will be so timed with the replenishing mechanism as to be under the magazine when the weft hammer not shown operates to move a bobbin from the 20 transfer position T shown at Fig. 1 into the depleted shuttle. The matter thus far described is of common construction and for a more complete description of the structure and operation thereof reference may be had to 25 Patent No. 1,030,748.

My invention relates more particularly to the device which holds the bobbin in transfer position. Each lower tie rod 14 may have 30 mounted thereon a holder 16 which is positioned both longitudinally and angularly with respect to the tie rod by a screw 17. In the preferred form of the invention shown in Fig. 1 each holder will be provided with 35 a hole or opening 18 extending downwardly and toward the position occupied by a bobbin awaiting transfer. Located in the bore of each holder is a coiled spring bobbin support 19 formed of coils which lie closely adjacent each other as set forth in Fig. 6. The lower end of the spring or support may have 40 driven thereunto a tip or bobbin positioner 20. The spring 19 and the tip 20 may be disposed as shown in Fig. 1, the front and 45 back supports being inclined in opposite directions so as to position the tip ends of the bobbins as will be understood from Fig. 2.

As previously stated the weft ends W which extend through slots 21 in the outer 50 plate are held in position by a thread holder indicated at H in Fig. 2. Said holder is ordinarily supported by the outer plate and may be positioned to assist the proper threading of the shuttle on the first pick following 55 transfer. In order to prevent the weft ends from becoming entangled with that portion of the surface of the spring 19 down which the bobbin rolls toward the tip 20 I provide an inherently elastic flexible tube 25 which 60 may conveniently take the form of a rubber finger and dispose the same with respect to the tip 20 and the support 19 as set forth in Fig. 6. If desired the shield or cover 25 may be sufficiently long to cover that portion 65 of the holder 19 which lies within the range

of movement of the bobbins located in the outer compartments or guideways. The effect of said shield 25 is to provide the bobbin support with a smooth continuous surface which is incapable of entangling the weft ends W, and also prevent undue rebound of 70 a bobbin as it reaches transfer position.

The form of holder shown in Fig. 6 is made with its coils all closely adjacent each other and as previously stated it occasionally 75 happens that a bobbin will be misplaced with respect to the lay and engage the lower end of the support as the lay is moving, the result of which is to break either the bobbin or alter the setting of the support. In order 80 to permit yielding on the part of the bobbin support I may make the same according to the modified form of my invention in Fig. 4 and provide the upper end of said support with a closed coil holding portion 30 extending 85 through the holder and clamped in position by a screw 31. The wire of which the holding portion 30 is formed may provide an intermediate portion formed of spaced or open coils 32. If it is not desired to use the 90 form of bobbin tip 20 in Fig. 6 the wire may be wound in the form of a cone as shown at 33 in Fig. 4, the cone 33 performing substantially the same function as that performed by the plug or tip 20 in the preferred 95 form of the invention.

It will be understood that the open coils 32, if unshielded, would interfere with the proper movement of the weft ends W as the bobbins move from the several stacks toward 100 transfer position in the magazine. In order to prevent this interference I provide a flexible and elastic shield 34 which may be similar to the shield 25. As shown in Fig. 4 it is not necessary for the shield to extend to 105 the bobbin engaging end of the support when the latter is formed as shown in Fig. 4. Should the plug as shown in the preferred form of the invention be employed, however, in connection with the lower end of 110 the support shown in Fig. 4, it might be desirable to have the rubber covering 34 extend around the plug. If desired of course 115 the conical end 33 may be covered in a manner similar to the covering of the tip 20 in Fig. 6.

In the modified form of the invention, however, there is present a feature which is not found in the preferred form, namely, that illustrated in Fig. 5, where it is assumed that a bobbin 40 is misplaced with respect to its shuttle and the lay. As the lay moves in the direction of arrow A the bobbin 40 is brought into endwise engagement with the support. Under these conditions the coils 32 will compress to absorb the shock incident to the engagement, the rubber tube or shield because of its inherent resilience assuming some such a form as shown in Fig. 5 130

and compressing more or less to the same degree as do the coils 32.

From the foregoing it will be seen that I have provided a very simple means for covering a coil spring bobbin support so as to avoid entanglement of the weft ends by the coils of the spring support. It will further be seen that in the modified form the bobbin support is compressible in a direction parallel to or in line with its axis and that after the deforming strain is removed the shield will be restored to its normal position. It is preferable to have the internal diameter of the shields 25 and 34 slightly less than the external diameter of the parts over which they fit so that said shields serve by their own resilience to hold themselves in position. With respect to Fig. 4 it will also be understood that the open coils which form the compressible part of the support lie partly at least in the path of movement of the bobbin which moves from one of the outer compartments toward transfer position and that the shield acts to prevent the weft end from entering between coils in this portion of the support. It will also be understood that the conical or lower pointed end of the support may or may not be covered by the shield depending upon the construction of the support, but in any instance it is desirable to have any portions of the support which might receive the weft threads covered by the shield so that the bobbins may move freely toward transfer position without interruption due to entanglement of the weft ends.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having reserve bobbins which are movable toward transfer position, a support to assist in holding a bobbin in transfer position, said support including a coil spring, and a resilient covering for said spring made of inherently elastic material to be engaged by the bobbin and the weft and extending therefrom as the bobbin moves toward transfer position.

2. In a weft replenishing loom having reserve bobbins which are movable toward transfer position, a bobbin supporting wire coiled on itself and yieldable in any angular direction with respect to the axis of the support, and a covering for the support made of inherently elastic material to be engaged by a bobbin and the weft ends extending from the latter as the bobbin moves toward transfer position.

3. In a weft replenishing loom having reserve bobbins which are movable toward transfer position, a bobbin supporting coil spring which is yieldable in any angular di-

rection with respect to the axis of said spring, and a rubber tubular covering fitting over the spring and positioned to be engaged by a bobbin and the weft extending therefrom as the bobbin moves toward transfer position.

4. In a weft replenishing loom having reserve bobbins which are movable toward transfer position, a bobbin supporting coil spring the bobbin supporting portion of which is yieldable in any angular direction with respect to the normal axis of the spring, and a shield for said spring formed of flexible material which may yield in any angular direction with respect to the normal axis of the support, said shield having a continuous surface located to be engaged by the bobbin and the weft extending therefrom as the bobbin moves toward transfer position.

5. In a weft replenishing loom having reserve bobbins which are movable toward transfer position, a support to assist in holding a bobbin in transfer position, and a flexible covering for said bobbin support capable of flexing at any point along the length thereof and positioned to engage a bobbin and the thread extending therefrom which is moving toward transfer position.

6. In a weft replenishing loom having reserve bobbins which are movable toward transfer position, a support to assist in holding a bobbin in transfer position, and a flexible covering for said bobbin support positioned to engage a bobbin and the thread extending therefrom which is moving toward transfer position, said covering presenting a substantially continuous surface to the weft end of the bobbin independently of the surface of the support.

7. In a weft replenishing loom having reserve bobbins which are movable toward transfer position, a support to assist in holding a bobbin in transfer position, said support including a spring certain of the coils of which are open and spaced from each other, and a flexible covering for the support lying over the coils which are spaced and presenting a substantially continuous surface to a bobbin which moves along the support toward transfer position.

8. In a weft replenishing loom having reserve bobbins which are movable toward transfer position, a support to assist in holding a bobbin in transfer position, said support including a wire coiled on itself and having coils which are spaced to permit a portion of said support to be compressed, and a flexible covering for the compressible portion of the support lying in the path of a bobbin and the thread extending therefrom when the thread and bobbin are moved toward transfer position.

9. In a weft replenishing loom having reserve bobbins which are movable toward transfer position, a support to assist in holding a bobbin in transfer position, said sup-

- port including a metallic substance and having a compressible non-continuous surface which lies along the path of movement of the bobbin moving toward transfer position, and a flexible cover for said non-continuous surface to present a continuous surface to the bobbin and the thread extending therefrom when the bobbin and thread are moving toward transfer position.
10. In a weft replenishing loom having reserve bobbins which are movable toward transfer position, a support to assist in holding a bobbin in transfer position, said support having a metallic compressible portion and having a non-metallic covering for the compressible portion to be engaged by a bobbin and the thread extending therefrom which is moving toward transfer position.
11. In a weft replenishing mechanism, means defining a pathway along which bobbins may move toward transfer position, a coil spring bobbin support extending into the pathway, that portion of the support lying in the pathway being formed of spaced coils, and a flexible cover for that portion of the support which extends into the path of the bobbin to present to the latter and the thread extending therefrom a substantially continuous surface.
30. 12. In a weft replenishing mechanism, means defining a substantially vertical compartment along which bobbins may move toward transfer position, a bobbin support located under said compartment and having one part lying on one side toward the transfer position of a bobbin and the other part lying on the other side of said compartment, said support being formed of a coil spring having the first named part formed of spaced coils, and a flexible device lying above said spaced coils to present a substantially continuous surface to a bobbin and the weft end extending therefrom which is moved toward transfer position.
45. 13. A bobbin support for a weft replenishing mechanism, said support comprising a coil spring and having a flexible and compressible shield to cover the spaces between the coils and present to a thread a substantially continuous surface.
55. 14. A bobbin support for a weft replenishing loom, said support being formed of a wire coiled on itself in the form of a spring, and an inherently flexible cover extending above the portion of said spring and having a continuous surface covering the spaces between coils of the spring to be engaged by a bobbin.
60. 15. A bobbin support for a weft replenishing loom, said support being formed of a coil spring a portion of which is compressible, and a flexible compressible covering for said compressible portion.
85. 16. A bobbin support for a weft replenishing loom, said bobbin support formed of a coil spring having a compressible portion and an inherently flexible compressible cover for said compressible portion.
17. A bobbin support for a weft replenishing loom, said bobbin support formed of a coil spring having a compressible portion and an inherently resilient compressible cover for said compressible portion, said cover being held to the support by its own resilience.
18. A bobbin support having compressible and non-compressible portions, the compressible portion having a non-continuous surface to lie in the path of movement of a bobbin moving toward transfer position, and a flexible cover for the compressible portion of the support.
- In testimony whereof I have hereunto affixed my signature.
- JOHN F. TINSLEY.
